James H. Gridley

United States Patent Office.

JAMES H. GRIDLEY, OF WASHINGTON, DISTRICT OF COLUMBIA, ASSIGNOR
TO S. F. DICKINSON, OF NEW YORK CITY.

Letters Patent No. 75,679, dated March 17, 1868.

IMPROVED MOP-WRINGER.

The Schedule referred to in these Letters Patent and making part of the same.

TO ALL WHOM IT MAY CONCERN:

Be it known that I, JAMES H. GRIDLEY, of the city and county of Washington, in the District of Columbia, have invented a new and improved Mop-Wringer; and I do hereby declare that the following is a full, clear, and exact description of the construction and operation of the same, reference being had to the annexed drawings, making a part of this specification, in which—

Figure 1 represents a vertical section through the line $z z$ of fig. 2.

Figure 2 is a top view.

The object of this invention is to produce a cheap, simple, and easily-operated device, which can be used in connection with a wash-tub, of any size or form, which will offer no impediment to the introduction of the mop into the tub, and which will express the water from the mop without any loss of time, with the application of but little power, and with no tendency to capsize the tub.

In the drawings, A represents the wash-tub, and B B are two parallel bars of wood that constitute the supporting-frame of the mop-wringer, resting on the top of the tub when the instrument is in use, as shown in figs. 1 and 2. C C¹ are two hinged or pivoted frames or boards, lying parallel to each other, and connecting the pieces B B. One of them, C¹, is pivoted at its lower edge, by means of journals at its extremities bearing in the inner edge of the pieces B B; the other, C, is pivoted in the same manner, but at a point above its lower edge, so that a portion of it, equal in extent to the frame C¹, rises above the top of the tub, while a portion, C², projects below the side-pieces into the tub.

A connecting-rod, D, extends from about the middle of the frame C¹ to the lower edge of the part, C², of the opposite frame, and a spiral spring, or an elastic, E, connects the lower edge of said part C² with some fixed point, e, on one of the side-pieces B B. The connecting-rod and spring may be employed at each end of the plates or boards C C¹, extending along the inner edge of each side-piece, as shown in fig. 2. Along the upper edge of each frame extends a roller, R, which rotates freely on its journals.

The instrument being set upon the top of a tub, as shown in the drawings, the operation of the spring E is such as to force the rollers R R apart, causing all parts of the apparatus to assume the position shown in dark lines in figs. 1 and 2, and leaving the tub open, so that there is nothing to obstruct the dipping of the mop into the water. The mop having been dipped is withdrawn, and, as it leaves the water, the operator places her foot upon one of the frames C C¹, and presses it down, bringing both rollers together against the mop, and causing all the parts of the apparatus to assume the position shown in the red lines. The parts being held in this position by her foot, she draws the mop up between the rollers, wringing the water from it just in proportion to the pressure exerted by her foot upon the hinged board.

This instrument, as will be observed from the brief description already given, is simple and cheap in construction, and can be used in connection with any kind of wash-tub. It requires no adjustment, and is operated by a simple pressure of the foot upon the hinged board or frames, requiring but a moment of time, and not even rendering it necessary to change the direction or position, nor to arrest the motion of the mop, in withdrawing it from the tub. When the foot is removed from the hinged board, the rollers separate automatically, leaving the tub open as before.

To prevent mop-wringers from slipping on the tubs with which they are used, they have been heretofore clamped to the side of the tub by a screw or some similar device. I fix mine firmly in position, however, without the use of any clamping-apparatus, by simply sinking its corners into notches cut in the top of the tub for the purpose, as shown at n n n n. Thus, dispensing with the clamp, I render the apparatus simpler and cheaper in construction, and more readily attachable to and removable from the tub than any hitherto in use.

Having thus described my invention, what I claim as new, and desire to secure by Letters Patent, is—

1. The combination of the pivoted boards or frames C C¹ with the connecting-rod D, in the manner and for the purposes set forth.

2. In combination with the boards C C¹, rod D, and spring E, I claim the rollers R R, substantially as and for the purpose specified.

3. I claim the above-described method of attaching the mop-wringer to the tub, when in use, to prevent its slipping upon the tub, substantially as set forth.

JAMES H. GRIDLEY.
